UNITED STATES PATENT OFFICE.

EARNEST PAUL GANGEWERE, OF CHATTANOOGA, TENNESSEE.

LOCK.

1,300,719.

Specification of Letters Patent. Patented Apr. 15, 1919.

Application filed September 3, 1918. Serial No. 252,414.

To all whom it may concern:

Be it known that I, EARNEST P. GANGEWERE, a citizen of the United States, and resident of Chattanooga, in the county of 5 Hamilton and State of Tennessee, have invented certain new and useful Improvements in Locks, of which the following is a specification.

This invention relates to a lock particularly designed for use upon railway freight cars, and an object of the invention 10 is to provide a lock which will act automatically to lock the doors when the latter is closed.

Another object of the invention is to provide a lock for the doors of said cars which is particularly designed for use in connection with the sliding doors and which is comparatively simple in construction, durable 15 and one which comprises a car body carried locking bolt normally held in operative position by a spring controlled tumbler and a door carried bolt, which upon projection through the casing of the car body carried 20 locking mechanism will release the bolt allowing it to fall downwardly through the car door carried bolt for locking the same.

Other objects of the invention will appear in the following detailed description, taken 25 in connection with the accompanying drawings, forming a part of this specification, and in which drawings:—

Figure 1 is a side elevation of the improved lock mechanism, showing the same 30 applied to a door.

Fig. 2 is a side elevation of the door carried locking bolt showing the manner in which the bolt may be swung backwardly over the door to eliminate any portion thereof from projecting beyond the free edge of 35 the door.

Fig. 3 is a section through the car body carried lock and

Fig. 4 is a horizontal section through the 40 door carried bolt showing the manner of attaching the same to the door.

Referring more particularly to the drawings, A indicates an ordinary railway freight car which has the usual type of sliding doors, supported and guided by the ordinary type of hangers or guides C. The 45 improved lock mechanism, which is generally indicated by the numeral 1, comprises the door carried structure 2, and the car 50 body carried structure 3 which latter is

carried by the car body in close proximity to the edge of the door opening.

The door carried mechanism 2 comprises the bolt 4, which has its inner end substantially rectangular in shape and provided 55 with an opening as clearly shown in Figs. 1 and 2 of the drawings, forming the rectangular open frame 5, from one end of which the bolt 4 projects. The end of the frame 5 opposite from the end upon which the bolt 4 is formed, is seated in a recess 6 formed in an attaching plate 7. The attaching plate 7 is attached to the door B of the car by bolts or rivets 8, and these bolts also serve to attach the locking bolt 4 to the car 60 door B, in that the end 9 of the frame 5 is rockably engaged in the recess 6 permitting the locking bolt to be swung so that it will extend beyond the edge of the door or swung 65 back upon the door as shown in Fig. 2 of the drawings, to prevent any portion of the mechanism 2 from projecting beyond the 70 edge of the door.

The car frame carried mechanism 3 comprises a casing 10 in which is slidably 75 mounted a locking bolt 11. The upper end of the locking bolt 11 is reduced, forming a shank 12 which projects out of the upper end of the casing, while the lower end of the locking bolt 11 tapers, for insertion 80 through the tapered opening 14 formed in the outer flat end 15 of the bolt 4 and the flattened end 15 is inserted through the openings 16 and 17 formed in the sides of the casing 10 near its lower end. The bolt 11 85 extends completely through the flat end 15 of the locking bolt 4 and through an opening 18 formed in the bottom of the casing 10, so that when this bolt extends through the opening 14 in the bolt 4, the door B will 90 be held securely in locked position, and the locking bolt 11 will be held against rattling or loose movement.

The locking bolt 11 has a shoulder 19 formed thereupon, which is engaged by the 95 pawl head 20 of the locking tumbler 21. The tumbler 21 is pivotally mounted upon a pin 22, within the casing 3 and a flat spring 24 engages the tumbler for holding the pawl head 20 in engagement with the shoulder 19 100 to support the locking bolt 11 in its upward unlocked position. The main body of the tumbler 21 extends downwardly in the casing 10 and is positioned in the path of 105 standing lugs 25 which are carried by the 110

- flattened end 15 of the locking bolt 4, so that when the locking bolt 4 is inserted through the openings 16 and 17, the upstanding lugs 25 will engage the tumbler 21 and rock the same, moving it into the dotted line position indicated in Fig. 3 of the drawings, and consequently releasing the support of the locking bolt 12, allowing the latter to drop downwardly, under its own weight for insertion through the openings 14 and 18 to lock the bolt 4 in place.
- The outer end of the bolt 4 extends entirely through the casing 10 and is provided with an opening 26 which aligns with an opening 27 formed in an angled bracket 28 carried by the casing 3. The alining openings 26 and 27 are provided for receiving the wire of the ordinary type of seal employed in sealing freight cars.
- When it is desired to open the door, after the seal has been broken, the bolt 11 is manually lifted out of the alining openings 14 and 18, and the door is moved into its open position. Immediately after the bolt 4 has been moved sufficiently to leave the tumbler 21, the flat spring 24 will force the tumbler forwardly, causing the pawl head 20 to engage the shoulder 19 and support the locking bolt 11 in its elevated position.
- It will be noted, by particular reference to Fig. 4 of the drawings, that the lugs 25 are positioned so that they will pass one upon each side of the lower tapered end of the locking bolt 11 upon the insertion or withdrawal of the end 15 of the bolt 4 into or from the casing 10.

Changes in details may be made without departing from the spirit of this invention, but;

40 I claim:

1. In a lock, the combination, of a door carried attaching plate, a locking bolt pivotally carried by said attaching plate and provided with a bolt receiving opening near its free end, a frame carried casing adapted to receive said pivoted bolt therethrough, a

gravity actuated locking bolt carried by said casing and adapted for projection through said opening, means for normally holding said gravity actuated locking bolt in a raised position, and means carried by said pivoted locking bolt for operating said bolt holding means to release the gravity actuated bolt upon insertion of the pivoted locking bolt into said casing.

2. In a lock, the combination, of a door carried bolt, means pivotally supporting said bolt, a frame carried casing, a gravity actuated bolt carried by said casing, a spring controlled tumbler normally supporting said gravity actuated bolt in an upward position, said casing provided with openings adapted to receive therethrough said door carried bolt, said door carried bolt provided with an opening extending vertically therethrough and lugs formed upon said door carried bolt for engaging said tumbler to rock the latter to permit said gravity actuated bolt to fall for insertion into the opening in said door carried bolt.

3. In a lock, the combination, of a door carried bolt, means pivotally supporting said bolt, a frame carried casing, a gravity actuated bolt carried by said casing, a spring controlled tumbler normally supporting said gravity actuated bolt in an upward position, said casing provided with openings adapted to receive therethrough said door carried bolt, said door carried bolt provided with an opening extending vertically therethrough and lugs formed upon said door carried bolt for engaging said tumbler to rock the latter to permit said gravity actuated bolt to fall for insertion into the opening in said door carried bolt, a bracket carried by said casing, the terminal of said door carried bolt adapted to extend through said casing and lie in close proximity to said bracket, the projecting end of said door carried bolt and said bracket being provided with alining openings to receive a seal wire.

EARNEST PAUL GANGEWERE
